UNITED STATES PATENT OFFICE.

WILLIAM D. LIGON, OF MONTCLAIR, NEW JERSEY.

SAFETY INCLOSED FUSE.

1,301,465.

Specification of Letters Patent.

Patented Apr. 22, 1919.

Application filed June 21, 1915. Serial No. 35,488.

To all whom it may concern:

Be it known that I, WILLIAM D. LIGON, a citizen of the United States, and residing at Montclair, in the county of Essex and State of New Jersey, have invented new and useful Improvements in Safety Inclosed Fuses, of which the following is a specification.

Heretofore safety inclosed fuses have usually been inclosed in a casing and surrounded with a filling material and the fuse link or wire soldered to terminals or the end caps, thus rendering it difficult to readily replace the fuse link when ruptured by the passage of an excessive electric current.

15 The construction of removable safety inclosed fuses in the past has not made possible the limiting of the size of fuse wires or strips extending between the internal terminals by means not easily altered, and for this reason such fuses cannot be said to have a fixed or definite rating.

20 My invention relates to improvement in safety inclosed fuses, and concerns the combination and construction of the terminals within the casing through which the fusible element is passed before forming a substantial contact with the exterior end terminals or connections.

25 I have discovered that such difficulties as above referred to, are best eliminated by attaching the terminals within the casing and so constructing same as to insure against the enlargement of the hole or aperture formed or made to receive a fuse wire or strip of 30 larger dimensions than those for which the fuse casing or body is designed. My improvements facilitate the proper adjustment of the fuse wire or link when renewing the "blown" fuse elements.

35 I obtain these objects by the construction shown and illustrated in the accompanying drawings, in which Figure 1 and Fig. 4 are cross sections of the entire fuse. Fig. 2 is an end view of terminal 5; Fig. 3 is an end view of terminal 6; Fig. 4 is a longitudinal section of a modified form of my invention; Fig. 5 is an end elevation of the fuse shown in Fig. 4; Fig. 6 is identical with the right hand end of Fig. 4 except that the disk or 40 washer 15 has been omitted.

45 Referring more particularly to the drawings, 1 are fusible elements contained within a tubular casing 2 having a cylindrical bore and containing the ordinary loose filling. 50 3-8 are plates which are carried by internal terminals 5 and 6 respectively. The ter-

55 minal 6 is provided with perforations 7, through which the elements 1 extend. The terminal 5 is provided with openings for the fuse elements on each side of its plate 3, 60 which openings terminate in a cone-shaped hole or mouth 4, the larger end of which is of substantially the same internal diameter as the internal diameter of the casing 2 and concentric therewith so as to act for a guide 65 for the forward ends of the elements 1 when they are fed into the casing through the holes 7 guiding them toward the openings on each side of the plate 3. The ends of the fusible elements are secured to the terminals 70 5 and 6 by screws 8. Surrounding the ends of the casing 2 are caps 9 which are provided with suitable slots so that they can be passed over the blades 3, which constitute 75 external terminals. These caps are secured 80 to the casing by screws 11. The inner ends of the blades 3 are held in slots 12 in the terminals 5 and 6. The terminals 5 and 6 are held within the casing. The casing contains the loose filling ordinarily used in 85 inclosed fuses. Adjacent to the terminals 6 and preferably in close proximity thereto is a disk 15 having holes which register with the holes 7. It is preferably of hardened steel or a substance difficult to machine or 90 drill and may be brazed or soldered to the terminal 6. Its holes are calibrated so as to determine the size of the fusible elements which can be inserted in the casing.

95 In order to renew the fusible elements in the fuse when blown, the caps 9 are first removed. The screws 8 are then loosened and the unburned portions of the fusible elements are drawn outward. New fusible elements are then introduced through the holes 7 in the terminal 6, the cone-shaped mouth serving to guide their forward ends so that they are easily passed through the openings in the terminal 5. When the fusible elements have been passed through the casing 100 in this manner, their forward and rear ends are clamped underneath the screws 8. The caps 9 are then restored to their places.

105 In the modification shown in Figs. 4 to 6, which is more applicable for a smaller sized fuse, 1 is the fusible element; 2 is the casing; 5^a and 6^a are terminals secured in the ends of the casing. The terminal 6^a has a perforation 7 and has adjacent to it a steel or other hardened disk 15 having a calibrated perforation registering with the perforation 7. The terminal 5^a has a cone-

shaped opening 4. Each of these two terminals has integral therewith a projection 13 having a cross-cut therein crossing the hole 7. These projections are screw-threaded. The fuse is provided with caps 9^A which extend down over the ends of the casing and are provided with holes having screw-threads adapted to engage with the screw-threads upon the projections 13 so as to hold 10 the caps in place and also to clamp the ends of the fusible element against the terminals 5^A and 6^A. In this modification, when it is desired to renew the fusible element, the caps 9^A are unscrewed and the unburned 15 portions of the fusible element drawn outward. A new fusible element is then fed inward through the hole 7 until its forward end, guided by the cone-shaped mouth 4, passes through the opening in the terminal 20 5^A. The ends of the fusible element are then bent downward in the cross-cuts 14 and twisted around the projections 13, after which the caps 9^A are screwed into place so as to securely clamp the ends of the fusible element. In this form the caps constitute the external terminals. It is to be noted that the fusible element is of such a size that all portions of it will pass through the 25 perforations in the terminal 6^A and the plate 15.

With the construction above described, the fusible element can be easily renewed without any substantial loss of the filling, and, furthermore, it is impossible to insert a fusible element of a greater capacity than the 30 fuse casing is designed to carry.

In these specifications the term "internal terminal" relates to terminals within the fuse casing as 5, 5^A, 6, and 6^A. "External terminal" refers to cup-shaped caps 9 and 9^A, 35 blades or connections 3, extending partially within the fuse and partially without the fuse.

In the foregoing I do not limit myself in 40 any way to the shape of the particular parts.

From the foregoing the operation of my safety inclosed fuse is easily understood. When the fusible element 1 has been ruptured by an excessive electrical current the 45 remaining parts may be easily removed by unscrewing the terminal 9^A in Fig. 4, or loosening the screws 8, in Fig. 1. The renewing of the fusible element is easily accomplished by passing the fuse wire or strip 50 through the hole 7, cone-shaped aperture 4,

and formed under the screw heads 8, or caps 9 and 9^A. The holes or apertures 7, are made to receive a fusible element or elements representing the maximum capacity of the casing, and in order to "load" the fuse to 60 a greater capacity it is necessary to enlarge the hole or aperture 7; which operation is made difficult by the use of metals not easily drilled or machined.

Having thus described my invention, I 65 claim—

1. In an inclosed safety fuse, the combination of a casing, a terminal at one end having a perforation, a terminal at the other end having a perforation, a fusible element 70 all parts of which can pass through said first perforation and whose forward end can pass through said second perforation, the inner end of said second perforation flaring so as to be of approximately the same diameter 75 as the internal diameter of said casing and act as a guide for the forward end of said element when inserted through said first perforation, said terminals being provided with screw-threaded external projections 80 having cross-cuts for the ends of said element, and caps inclosing the ends of said casing and having screw-threaded openings making engagement with said projections, 85 and clamping the ends of said element. 85

2. In an inclosed safety fuse, the combination of a casing, a terminal at one end having a perforation, a terminal at the other end having a perforation, a fusible element all 90 parts of which can pass through said first perforation and whose forward end can pass through said second perforation, means for securing the ends of said fusible element, the inner end of said second perforation flaring so as to be of approximately the same diameter 95 as the internal diameter of said casing and act as a guide for the forward end of said element when inserted through said first perforation, and a hardened steel disk within said casing and adjacent to said first 100 terminal and having the inner surface of a calibrated hole in alinement with said perforation therein.

Signed by me this 5th day of February, 1915.

WILLIAM D. LIGON.
